UNITED STATES PATENT OFFICE.

ROBERT CHARLES SHARP, OF APPLE CREEK, OHIO.

APPARATUS FOR TRANSFERRING MAIL-POUCHES.

No. 880,409.

Specification of Letters Patent.

Patented Feb. 25, 1908.

Application filed October 31, 1907. Serial No. 400,063.

To all whom it may concern:

Be it known that I, ROBERT CHARLES SHARP, a citizen of the United States, residing at Apple Creek, in the county of Wayne and State of Ohio, have invented certain new and useful Improvements in Apparatus for Transferring Mail-Pouches; and I do hereby declare the following to be a full, clear, and exact description of the invention, 10 such as will enable others skilled in the art to which it appertains to make and use the same.

My invention relates to apparatus for transferring mail pouches, receptacles or 15 other articles of merchandise, to and from fast moving mail or express trains, with accuracy and with entire safety to the contents of such pouches, receptacles and articles, or to the persons engaged in receiving 20 and delivering them.

More particularly stated the present invention contemplates a novel extension and arrangement of the ordinary mail-catcher or collector, whereby a suspended pouch may 25 be automatically released and delivered, or transferred, to an inclined trolley wire or cable at stations equipped for exchanging mail.

The invention for accomplishing the aforesaid objects in an improved and most satisfactory manner, consists in the construction, 30 novel combination and arrangement of parts hereinafter described and particularly pointed out in the claims following.

In the accompanying drawings, which 35 form part of this application, and whereon like numerals of reference indicate corresponding parts in the several views: Figure 1, represents in side elevation the body of a mail car equipped with my improved catcher 40 and deliverer from which is suspended a mail pouch, and adjacent thereto is shown an inclined cable partly broken away, for economy of space on the drawing, and positioned to receive said pouch. Fig. 2, is a 45 plan view of the catcher and deliverer, the receiving end of the cable, and the overhanging horizontal support therefor. Fig. 3, is a plan view partly in section of the automatic cast-off mechanism. Fig. 4, is a side 50 elevation of parts shown by Fig. 3. Fig. 5 is a transverse section taken on the line 5—5, Fig. 3. Fig. 6 is also a transverse section on the line 6—6 Fig. 3.

Reference being had to the drawings and 55 numerals thereon, 1 indicates the body of a mail car upon which are secured the usual

collector-brackets 2, 2, at opposite sides of the car door. In said brackets is pivotally mounted the ordinary catcher or mail-receiver 3, which however, in this instance, is folded upon itself to form a continuation 4 hereinafter termed the body member of the mail deliverer. The trailing end of said body 4 is squared as shown at 5 Fig. 3 and is recessed or notched as at 6 for purposes that will later appear. Upon said squared end or shank 5 of body 4 is socketed a detachable carrier 7, which again folding upon itself diverges and terminates in a gatherer 8, at a point in advance of its socketed connection. 70

Surrounding and secured to the carrier 7 is a shackle 9 to which the mail bag, ready for delivery, may be attached. While at a point between said shackle and the socketed end of said carrier, is pivotally connected a latch 75 or trigger 10 having a bifurcated trailing end 11—11 and an angular advance end 12 as best shown by Fig. 3. Normally the ends 11—11 are elevated, and the advance end 12 depressed by action of a suitable spring 13 interposed between said latch and its supporting carrier at a point back of its pivotal connection, and in such position the end 12 passing through slot 14 of the socket aforesaid enters notch 6 to retain said body member 4 and carrier 7 in locked relation. 80

Adjacent to and by preference parallel with the tracks or line of travel at receiving stations, is an upwardly inclined receiving line wire or cable 15 of sufficient length to 90 gradually overcome the inertia of a mail pouch when transferred thereto from a rapidly running train. This line or cable 15 is securely affixed to horizontal overhanging arms 16 projected from suitable uprights 95 17—17 which it connects, and, upon it is a trolley wheel 18 having a depending chain 19 held taut by a weight 20 at its lowermost end for purposes that will now appear in a brief description of the use and operation of my 100 invention.

Presuming for example that a mail pouch has been suspended from shackle 9 as indicated by Fig. 1, and that the mail car moving in the direction indicated by the arrow in 105 Fig. 2, is approaching a receiving station properly equipped. Obviously, as the weighted depending chain 19 is gathered into the diverging terminal arm 8, the bifurcated or trailing ends 11—11 of latch 10 are depressed and its advance angular end 12 withdrawn from locking engagement with notch 110

6 in shank 5. Thus automatically released, the ordinary mail catcher or collector 3 together with the body member 4, passes on with car 1 while the detachable and now detached carrier 7, with the bifurcated ends 11-11 of latch 10 embracing a link of pendant chain 19, is transferred to the cable 15. Traversing said cable in an upward direction by agency of the trolley wheel 18 the inertia 10 of the pouch and carrier is gradually overcome by gravity and the pouch is finally returned to the lowermost or starting point upon said cable to be removed by an attendant. Thus it will be noted an exchange of 15 mail pouches or similar articles may be made instantaneously, for while one pouch is being delivered as above described, another may, if desired, be gathered into the collector 3, in the ordinary manner from a suitable crane or 20 support on the roadside.

It may be noted also that various changes in the construction and arrangement of parts may be made and substituted for those shown and described without departing from the 25 spirit of my invention; for example, cable 15 may vary in length, its angle of inclination, or both, according to speed requirements; or said cable may be rendered vertically adjustable at one end for similar reasons.

30 Having thus described my invention, what I claim and desire to secure by Letters Patent is:

1. In an apparatus of the class described the combination with a mail bag catcher, of 35 a detachable pouch supporting carrier mounted upon said catcher, a receiving line, and means interposed between said line and carrier for automatically releasing said carrier and transferring it to the line aforesaid, 40 substantially as described.

2. In an apparatus of the class described the combination with a car, of a pouch-supporting carrier comprising a body member and a detachable member, a latch for 45 interlocking said members, a fixed receiving line and a pendant from said line for engaging said latch to automatically release and transfer said detachable pouch-carrying member to the receiving line aforesaid, substantially as described.

3. In an apparatus of the class described

the combination with a car, of a pouch-supporting carrier comprising a body member and a detachable member, a spring-pressed latch for interlocking said members 55 having a raised bifurcated extremity, an inclined receiving line, and a chain depending from said line in the path of said latch-extremity whereby said detachable pouch-carrying member is automatically released 60 and transferred to the receiving line aforesaid, substantially as described.

4. In an apparatus of the class described the combination with a car having mounted thereon a mail collector and deliverer, the 65 latter comprising relatively fixed and detachable pouch-carrying members, of a latch for interlocking said members, and means at the receiving station for disengaging said latch to release said detachable 70 pouch-carrying member, substantially as described.

5. In an apparatus of the class described the combination with a car having mounted thereon a mail collector and deliverer, the 75 latter comprising relatively fixed and detachable pouch-carrying members, of a latch for interlocking said members having a normally elevated bifurcated trailing extremity, and a pendant at the receiving 80 station in the path of said latch-extremity for releasing said detachable pouch-carrying member, substantially as described.

6. In an apparatus of the class described the combination with a car having mounted 85 thereon a mail collector and deliverer, substantially S shape in form comprising relatively fixed and detachable pouch-carrying members, of a latch for interlocking said members, a fixed receiving line at the receiving station, and a trolley-mounted pendant upon said line in the path of the latch aforesaid for releasing said detachable pouch-carrying member and transferring same to the receiving line aforesaid, substantially as 90 described.

In testimony whereof I affix my signature, in presence of two subscribing witnesses.

ROBERT CHARLES SHARP.
